[57] ABSTRACT

Lift planning apparatus for computing the required

length, angular position, and free capacity of the boom of a crane apparatus, especially where the apparatus must work in a confined space.

The apparatus of the invention includes a base scale calibrated into predetermined horizontal and vertical units related to distance; a protractor indicative of a crane; and a replica of a boom and a point section.

The replica of the protractor, boom, and point section are arranged relative to the base scale so that various objects located within the area in which the actual crane is to work can likewise be scaled and placed onto the base scale thereby enabling one to ascertain by computation the optimum length and angular displacement of the boom.

The apparatus further includes a replica of a jib having a point section slidably received thereon, with the jib being journaled to a second protractor, and with the second protractor being slidably captured along the replica of the boom, thereby enabling the optimum boom length and angular displacement, the optimum jib length and angular displacement, and the free lifting capacity at either of the point sections to be calculated.

LIFT PLANNING APPARATUS

BACKGROUND OF THE INVENTION

In erecting and dismantling structures such as large vessels, electrical motors, ventilation equipment, buildings and the like, especially where the construction is being carried out in a crowded area such as a complex petro-chemical plant or the like, it is necessary to use a lifting device, such as a crane, in order to provide an overhanging structure from which an object can be lifted vertically and moved horizontally while clearing the surrounding structure.

Often a contractor will move his crane onto location in preparation for the installation of a vessel, position the boom at its optimum angle relative to the horizontal, and upon lifting the vessel with the point section of the boom discover that it will strike the boom before sufficient vertical clearance is attained to enable swinging the vessel horizontally into the new location. At other times a contractor will ship his crane apparatus to the location, and after the job of installation has commenced, discover that the improper boom length has been employed for lifting a specified load a particular vertical height.

A jib is useful in reaching out to great radial distances from the crane; however, in lifting loads with such a device, extreme caution must be taken to prevent overloading the structure. When employing a jib for lifting loads of significant weight many different complex factors must be considered, such as, for example: the free load capacity of the boom; the angular displacement of the boom; the attachment point of the jib relative to the boom; and the length and angular displacement of the jib relative to the boom. A jib usually is operated at or near maximum working capacity and for this reason it is desirable that the length of the jib and the boom as well as the angular displacement of the jib and boom relative to one another and to the horizontal be placed at the most advantageous position relative to handling a maximum free load while maneuvering within the confines of a particular working area.

Heretofore, it has been common for the contractor to rely upon a "trial and error" solution to this perplexing problem which often requires many hours of scaling and computation in order to arrive at a satisfactory boom length, jib length, and the relative angle between the boom, jib and horizontal. Moreover, once the computations have been completed, not only is it necessary to make absolutely certain that there is sufficient clearance for operating the crane, the boom, and the jib, but also assure that the load to be transported can be lifted a sufficient vertical height while maintaining an adequate radius of turn to clear all of the surrounding obstacles.

It would therefore be desirable to have made available a lift planning apparatus for computing the length, angular displacement, and free capacity of a boom. Further, it would be advantageous to compute these variables for a boom having a jib attached thereto. It would be desirable that such an apparatus be made available in a convenient form whereby a scale model of the existing structure which is to be relocated, as well as the surrounding structure within the working area, could all be assembled rapidly in more or less graphic form to thereby positively endow the contractor with confidence in his infallibility to compute all of

the ramifications necessary to erect or dismantle vessels and other objects in close working quarters.

SUMMARY OF THE INVENTION

5 This invention comprehends a lift planning apparatus in the form of a scaled model for computing the length, angular position, and free capacity of a boom. A base scale receives a crane protractor thereon which is indicative of a crane or the like, a replica of a boom 10 is affixed to and depends from the protractor and has a journaled end which enables the angular displacement relative to the replica of the crane to be measured. A replica of a point-section is slidably received upon the replica of the boom and enables the optimum length of the boom to be rapidly ascertained.

The invention further comprehends a second protractor slidably received longitudinally on the replica of the boom. A jib replica is journaled to the protractor so that the angular displacement of the jib relative to 20 the boom can be determined rapidly. A second point section replica is slidably received longitudinally on the jib replica so as to rapidly determine the optimum length thereof.

The base scale preferably is of a material which can 25 be cleaned of grease pencil, lead pencil, and the like, so as to enable either cutouts or indicia representative of the surrounding structure to be removably placed thereon.

It is therefore a primary object of the present invention 30 to provide lift planning apparatus for computing the length, angular position, and free capacity of a crane and boom combination.

Another object of the invention is to provide a lift planning apparatus for computing the length and angular 35 position of a boom and jib of a crane apparatus.

A further object of this invention is to provide apparatus for computing and planning the necessary crane apparatus to be employed in relocating a structure.

A still further object of this invention is to disclose 40 and provide improvements in lift planning apparatus, related to crane apparatus, which include a protractor, and a replica of a boom and a point section all movable relative to one another and to a base scale.

Another and still further object is to provide lift planning 45 apparatus which includes a protractor having a replica of a boom pivotally attached thereto and a replica of a point-section slidably received thereon, and further including a jib protractor slidably received on the boom and having a replica of a jib pivotally attached thereto and on which there is slidably received a replica of a jib point section thereby enabling a work area or a specific scaled geographical location to be reproduced in scaled relationship therewith.

An additional object of the present invention is to 55 provide means by which the problems involved in moving structure with a crane apparatus may be resolved by special scaled pictorial representations thereof.

These and various other objects and advantages of the invention will become readily apparent to those skilled in the art upon reading the following detailed description and claims and by referring to the accompanying drawings.

The above objects are attained in accordance with 60 the present invention by the provision of a combination of elements which are fabricated in a manner substantially as described in the above abstract and summary.

BRIEF DESCRIPTION OF THE DRAWINGS

FIG. 1 is a diagrammatical representation of the present invention illustrated in one of its practical working configurations;

FIG. 2 is an enlarged, broken, top plan view of a portion of the apparatus disclosed in FIG. 1;

FIG. 3 is an enlarged, fragmentary, top view of part of the apparatus disclosed in FIG. 1;

FIG. 4 discloses part of the apparatus seen in FIGS. 1 and 2;

FIG. 5 is a cross-sectional view taken along line 5—5 of FIG. 3, but with the apparatus being illustrated in a slightly different operating configuration;

FIG. 6 is an enlarged, fragmentary representation of 15 a portion of the apparatus disclosed in FIG. 1;

FIG. 7 is a cross-sectional view taken along line 7—7 of FIG. 6;

FIG. 8 is an enlarged fragmentary representation of 20 part of the apparatus disclosed in FIG. 1; and

FIG. 9 is a cross-sectional view taken along line 9—9 of FIG. 8.

DETAILED DESCRIPTION OF THE EMBODIMENTS

FIG. 1 discloses a lift planning apparatus for computing the length, angular position, and free capacity of a crane apparatus made in accordance with the present invention.

Throughout this disclosure the term "crane" relates to both stationary and movable crane devices adapted to pivotally support a boom mounted in journaled relationship thereto. The term "point-section" relates to apparatus indicative of the removable portion of the free end of the boom which is located spaced apart from the pivoted end of the boom and having a sheave therein so as to enable a cable or the like to be rove about a drum placed within the crane and stretched upwardly to the sheave, then vertically downward to a block, and then usually back up to a location in close proximity to the sheave located in the point-section. The term "jib" relates to a secondary smaller boom which usually is pivotally attached to an intermediate portion of the main boom, and depends therefrom and generally includes a point-section associated therewith having a sheave located therein in the before described manner. The term "crane apparatus" is intended to include the crane, booms, and point section.

The term "base scale" relates to a flat horizontal surface upon which indicia has been placed with the indicia being related to scale of an actual crane, boom and jib apparatus. A replica of crane apparatus made in accordance with this invention can be slidably supported upon the base scale in a manner similar to placing a book upon the top surface of a desk or the like.

As seen in FIG. 1, a base scale 15 has a top surface formed into a plane upon which replica of crane apparatus 16 is slidably supported. The base scale includes vertical and horizontal intersecting lines 17. Various upstanding scaled structure 18, 19, and 20 have been included on the base scale by either drawing the structure with a lead or grease pencil, or alternatively, by actually cutting the scaled structure from paper so as to enable it to be slidably and removably positioned as desired.

Numeral 21 and 121 indicates a replica of a vessel which is to be either removed from or installed into the

illustrated position. Structure 21 and 121 preferably is a cutout made of paper, plastic, or the like, so that the cutout can be moved relative to the base scale and to the scaled crane apparatus.

5 A crane protractor 22, indicative of a crane vehicle body, is indexed with the arbitrarily chosen ground level 23 so that pivot point at journal 24 of the crane apparatus is arranged horizontally disposed above the ground level in the same relative position that the actual crane would be situated in its real environment.

The before mentioned journal 24 receives the journaled end of a replica of a boom 25 therein so that the pivoted end 26 of the boom can be pivoted in a vertical plane about the journal as may be deemed desirable.

10 A jib protractor 27 has a journal 28 formed thereon so that the journaled end of a replica of a jib 29 can be received thereon with the free depending end 30 of the jib pivoting in a vertical plane about its associate journal. A replica of a boom point section 31 is superimposed upon the boom replica in a slidable manner so that the point section can be arbitrarily positioned anywhere along the longitudinal length of the boom.

15 It will be noted that spaced apart cables vertically depend from each of the point sections; however, in actual practice of the invention the presence of these elements is not required.

20 In FIG. 2 there is seen the before mentioned replica boom having opposed parallel longitudinally extending edge portions 31, 31' equally spaced from center line 32. Parallel longitudinally extending spaced apart lines 32, 232 are scaled representations of booms of various widths and capacity. Numeral 33 is an extension of center line 32 and forms a pointer for use in conjunction with the before mentioned boom protractor. Numeral 34 indicates the terminal end of the journaled end portion of the boom replica which is provided with a constant radius of curvature with the center thereof intersecting the journal 24.

25 In FIG. 3, numeral 35 indicates the upper face of the before mentioned boom protractor, which has indicia 36 provided thereon related to ground level so that the boom pivot point of the crane apparatus can be located above ground level at a precise location which coincides with any desired actual working model of a crane. Numeral 37' indicates indicia related to the 0° to 90° of a protractor with the indicia being placed adjacent to the before mentioned pointer 33.

30 Fastener means 38 forms part of the before mentioned journal means. Spacer 39 underlays the upper plate member and provides reinforcement as well as maintaining the entire scaled crane apparatus in proper aligned relationship when it is supported on the base scale.

35 As seen in FIG. 5, in conjunction with FIGS. 3 and 4, the spacer includes edge portions 40, 41 laying normal to one another and similar edge portions 42, 43 with edge portion 44 having a portion thereof formed with a radius of curvature which receives the curved end portion 34 of the boom closely adjacent thereto so that the edge portions are slightly spaced apart as they move relative to one another.

40 As seen in FIG. 5, the journal is comprised of a pin member having an enlargement in the form of a washer 45 which is reduced in diameter at 46 so as to enable it to be received through the axially aligned apertures which are formed within the scaled boom and the boom protractor. Washer 47 is affixed to the thimble in

spaced opposed relationship with respect to washer 45.

FIGS. 6 and 7 disclose the details of the jib replica and its relationship to the boom replica and attachment plate 27, also called a jib protractor. Formed on the attachment plate is indicia 49 related to 0° to 90°. The jib replica and protractor is indexed at 0° when the jib is superimposed in parallel relationship with respect to the center line of the scaled boom. The jib replica includes a journaled end 50, a free end 51, and spaced apart parallel sides 52, 53. The journal means includes a fastener 54 formed along center line 55 with the jib protractor being indexed with the scaled boom so that the vertical axial axis of the journal means extends through centerline 32 of the scaled boom.

The jib protractor is provided with an upwardly directed plane or face 27 which is provided with the before mentioned indicia, with a marginal edge portion of the protractor being twice bent 90° so as to provide a vertical edge portion 56 and a horizontal edge portion which terminates at 57, thereby leaving a longitudinally extending groove within which a marginal edge portion 31 of the scaled boom is slidably captured in a manner to maintain the protractor properly indexed with the center line of the scaled boom. Countersunk nut 59 threadedly receives the fastener means therein, although a hollow rivet or other type fastener means could be used in its stead.

FIG. 8 illustrates the details of the replica of the boom point section 31. The point section is provided with means forming indicia at 61, 62 which is related to the physical size of the boom and which terminates at point 132. Point 132 preferably terminates slightly short of the forward edge portion 63. Longitudinally extending opposed marginal edge portions of the plate are provided with two 90° bends so as to provide a vertical edge portion 64 and a horizontal edge portion 65 which terminates in parallel spaced relationship with respect to similar edge portion 65', thereby leaving opposed cavities 66 within which the longitudinally extending parallel marginal edge portions of the scaled boom is slidably received.

Point section replica 67 is similar to point section replica 31 except for size and for the indicia provided thereon. Point section 67 is slidably received upon the jib replica in the same illustrated manner of the before described boom point section replica.

OPERATION

In operation, the base scale is laid out with the lines forming grid 17 being spaced apart a sufficient amount to provide a scale identical to the scale of the various components of the crane apparatus, preferably with the horizontal and vertical grids extending 300 feet in scaled length while using a scale of one tenth inch/foot thereby requiring a planar surface having a physical working area of 30 inches by 30 inches. Ground level 23 is selected and the obstructions 18, 19, 20 drawn or otherwise removably placed onto the base scale using a grease pencil, lead pencil, or paper cut-outs. Hence, the materials of construction of the base scale preferably are of a plastic-like durable finish which will admit of this practice.

The vessel 21 which is to be placed into the illustrated position of FIG. 1 preferably is a cutout from a piece of paper so as to enable it to be moved freely about the board in any desirable manner representative

of the actual contemplated working conditions to be encountered at the working area later on.

The boom protractor 22 is next placed relative to the ground level 23 so that journal 38 is vertically positioned in the same relative vertical position as the actual crane contemplated to be used. The protractor is next slid horizontally into its contemplated working area upon the base scale.

The boom replica 25 is pivotally adjusted so that it 10 clears all of the obstructions, and yet is at a reasonable angle for supporting the proposed hypothetical load therefrom. Jib replica 29 is next positioned at its optimum angle and the replica of the jib point section adjusted thereon so that the end thereof is axially aligned 15 with the scaled vessel to be lifted and moved. Vessel 21, at this stage of the operation, should be physically moved vertically upwards into proximity of the point section replica 67, and then the entire crane apparatus should be moved horizontally into the position where 20 it is contemplated that the scaled vessel will be set down. This operation assures that the various angles and lengths of the boom and jib will be satisfactory under the existing working conditions. Next it is necessary to select the proper boom and jib sizes by referring to the boom and jib tables. One example of a boom 25 table is as follows:

90 TON CRANE
MAIN BOOM (loads in Pounds)

Oper. Radius Feet	50' Boom	100' Boom	150' Boom	200' Boom
20	122,000	—	—	—
40	44,000	43,000	42,000	—
60	—	24,000	23,000	22,000
80	—	16,000	15,200	14,000
100	—	11,000	10,000	9,000

One example of a jib table is as follows:

JIB RATINGS in POUNDS

Jib/Boom Angle	20'	30'	40'	50'	60'
10°	21,000	19,000	15,000	11,000	7,000
20°	15,000	13,900	11,000	8,600	6,000
30°	12,000	10,500	7,600	6,200	5,700

Those skilled in the art will realize that each particular crane and boom combination will require a different 50 set of tables. In the above example, assuming the vessel 21 weighs 5,500 pounds; that the jib is set 30° respective of the boom; that the jib is 60 feet in effective length; and that the boom is 150 feet in effective length; that the angle of the boom provides a radius of 100 feet; the following data can be selected from the table: the jib point section describes a radius of approximately 200 feet, and the main boom can carry 9,000 pounds at a radius of 200 feet, and accordingly will adequately support a load of 5,500 pounds. However, the jib table indicates that at 30° and 60 feet the jib will safely support a load of only 5,700 pounds.

It is therefore evident that extreme caution must be employed if these selected values of the boom and jib are maintained because the entire apparatus will be working extremely close to its maximum working capacity. Those skilled in the art will realize that the above dangerous selected configuration of the boom

and jib could be alleviated by merely selecting a different boom and jib length and perhaps by decreasing the angle of the jib relative to the boom. It is evident, having read the foregoing parts of this disclosure, that one could rapidly compute a more favorable configuration by repeating the above described procedure.

Where working conditions make it desirable to lift a scaled vessel 121 from scaled point-section 131 of the replica of the boom, the present invention is invaluable in that it provides an actual working model of the conditions to be encountered upon location. In the example of FIG. 1, when the cutout 121 is lifted vertically upwardly a sufficient amount to clear obstruction 20', it is evident that the top of the scaled vessel will strike the boom replica prior to being lifted a sufficient height to clear obstruction 20'. For this reason it is necessary that the width of the actual boom to be used and any surrounding structure be scaled and furthermore herein lies one of the major teachings of this invention. To overcome this problem, it is elementary that a longer boom must be employed with the crane protractor being moved horizontally further away from obstruction 20'.

As a further example of the utility of the present invention, assume that a vessel 100 feet high and 12 feet in diameter is to be lifted only the amount required to move the vessel horizontally. Using line 232 of boom replica 31 which represents a 90 ton boom, and positioning the scaled crane and boom adjacent to a scaled cut-out of the load, it is evident that a 150 foot boom length set at an angle to provide a 25 foot radius is the minimum requirements for accomplishing the job. This provides a boom angle of 82° to the horizontal which is undesirable, and accordingly, employment of a 35 longer boom which is disposed at a safer angle is desirable.

In setting an air conditioning package on the top of a 60 foot roof, wherein the package weighs 1,200 pounds and must be disposed 50 feet from the nearest edge of the roof, it can be rapidly determined that a 110 foot main boom with a 50 foot jib set 15° will adequately handle and position the load.

It is always desirable to determine the angle 37' of the boom relative to the horizontal so that the crane 45 operator can easily set his actual boom at the previously calculated angle, thereby taking full advantage of the present invention. Most cranes have a protractor provided thereon which can be used to accomplish this portion of the invention.

The replica of the protractors, boom, jib, and point sections preferably are made of clear plastic or plastic-like material so that the necessary portions can be viewed through one another. For example, in the embodiment of FIG. 3, it is necessary that the protractor face 35 be made of clear plastic material so as to enable arrow 33 to be viewed therethrough. Should it be deemed desirable to make the protractor face 35 of non-transparent material, it would be necessary for boom 25 to be located in superimposed overlying relationship relative to the protractor so as to enable a pointer, equivalent to pointer 33, to be properly indexed with scale 37.

It is preferred to build the boom replica of plastic, such as plexiglass (TM) so as to enable point 132 to be indexed easily with the scale provided on the replica of the boom and jib.

Likewise, it is preferred that the second protractor be made of transparent material so as to enable journal 54 to be indexed with the indicia placed on the scaled boom. It will be noted by those skilled in the art that 5 opposed longitudinally extending parallel lines 132 are scaled for a 45 ton crane, while lines 232 are scaled for a 90 ton crane. The outermost edge portions of the scaled boom may be utilized as being a scaled representation of still a larger boom. For example, using 1 inch 10 = 8 feet, the boom width indicated by numeral 232 for a 90 ton crane apparatus would be approximately 1 inch in scale, that is, 8 feet in actual rectangular cross-sectional area for crane equipment of conventional design.

I claim:

1. Lift planning apparatus representative of crane apparatus for computing the length, angular position, and free capacity of a boom comprising:

a base scale, means by which said base scale is calibrated into horizontal and vertical units related to distance;

a crane protractor indicative of a crane; an elongated boom replica, a boom point section replica; said boom replica having a free end and an opposed journaled end, means by which said journaled end is affixed to said crane protractor, means by which said point section replica is slidably received in indexed relationship respective of said boom replica;

means by which said crane protractor, boom replica, and boom point section replica are slidably supported for movement on said base scale; said boom replica having means thereon cooperative with said protractor for determining the angle said boom replica is displaced from the horizontal; said boom replica having means forming indicia thereon forming a scale related to the width and length thereof with said scale being calibrated into said units; whereby;

said crane protractor and boom replica can be laid on said base scale along with scaled means representative of the area in which the working crane apparatus is to be used, and the optimum length and angle of the boom for achieving a predetermined free load capacity can be computed.

2. The lift planning apparatus of claim 1, and further including a jib protractor slidably received on said boom replica, an elongated jib replica having a free end and a journaled end, means by which said journaled end is journaled to said jib protractor; and, a jib point section replica slidably received on said jib replica;

whereby: said length and angle of said jib replica can be computed by pivoting the jib replica into a desired position for lifting, and noting its angular relationship relative to the boom replica on the jib protractor.

3. The lift apparatus of claim 2 wherein said crane protractor is provided with indicia related to 90° of arc, said indicia being arranged relative to a portion of said boom replica so that a portion of said boom is indexed with said indicia to indicate the relative angular position of the boom replica relative to the horizon;

said jib protractor being provided with indicia related to 90° of arc, said indicia being arranged relative to the boom and jib replica to indicate the relative angle therebetween.

4. The lift apparatus of claim 1 wherein said crane protractor is provided with indicia related to 90° of arc, said indicia being arranged relative to a portion of said boom replica so that a portion of said boom replica is indexed with said indicia to indicate the relative angular position of the boom replica relative to the horizon;

said jib protractor being provided with indicia related to 90° of arc, said indicia being arranged relative to the boom and jib replica to indicate the relative angle therebetween.

5. The lift apparatus of claim 1 wherein said crane protractor has a flat surface area defined by edge portions, a reinforcement underlying said flat surface with an edge portion of said reinforcement being concave in form; said boom replica underlying said flat surface and having a curved end portion received within said con-

cavity, with the lower face of said reinforcement forming a support means for said boom replica and said crane protractor.

6. The lift apparatus of claim 1 wherein said jib protractor includes a cavity within which the boom replica is slidably received; said jib replica being journaled to said jib protractor with said journal being aligned with the longitudinally extending center line of said boom and said jib replica.

7. The lift apparatus of claim 1 wherein said jib and boom point section replicas are each made of transparent material, indicia formed on the material related to a sheave, opposed cavities formed in each said point sections respectively, for receiving said jib and boom replica therein, respectively.
